HEADLEY TOWNSEND BACKHOUSE, OF WALTHAMSTOW, LONDON, ENGLAND.

SHEET-FEEDING APPARATUS FOR PRINTING MACHINES OR OTHER MACHINES
OPERATING ON PAPER SHEETS.

Application filed November 28, 1924, Serial No. 752,784, and in Great Britain November 30, 1923.

This invention relates to sheet-feeding apparatus for printing machines or other machines operating on paper sheets and to the so-called "endless" bands used in the conveyance of sheets to the registering or "equivalent" devices of the machine. It is an object of this invention to remove certain disadvantages which have been found to arise from the use of the usual conveyor bands.

In sheet-feeding apparatus employing endless bands for the conveyance of the sheets to the registering devices, the sheets are carried forward one at a time on the upper laps of the bands to a position in which the leading edge of the sheet comes into contact with and is temporarily arrested by two or more stops usually termed "lays" or "lay marks" which ensure that each sheet in succession is brought into the same position, as regards the alignment of its forward edge, before being passed on to the printing or other machine.

Hitherto the conveyor bands used for the above purpose have not, strictly speaking, been "endless". Each band has been constituted by a length of tape, the two ends of which after being passed round the driving shafts or spindles have been joined together by some form of fastener or by sewing or cementing. In the region of a joint there may be, and generally are, portions either of the tape or of the fasteners which project above the otherwise flush upper surface of the tape, and it is these projections which are liable to cause faulty registration of the sheets. It will be understood that when a sheet is arrested by the front lays a rear portion of that sheet still overlies the conveyor bands, and that said bands continue to travel while the sheet is temporarily at rest. It is during this period that a projection at the joint in a conveyor tape may engage the rear edge of the sheet and upset the alignment thereof. The greater the number of tapes employed the greater is the chance that the rear edge of a sheet will be fouled at some place or other by the advancing tapes.

According to this invention the conveyor bands are in the form of tapes which are constituted "endless" in the course of their manufacture. They may be woven in the form of truly endless bands, such as the tape known in commerce as the "Scandi-

navian" woven belt. Again they may be built up from a length of material, the two ends of which are joined during manufacture in such a way as to present a substantially flush outer surface. It will be appreciated that the surface which can be provided on a manufactured article of this type is considerably more uniform than it is possible to obtain on a tape having ends which are joined together by fasteners or otherwise after assembly. The tapes employed in carrying out the invention are therefore characterized by the absence of any projections at joints in the tape or elsewhere which would be liable in the circumstances hereinbefore explained to engage behind and foul the rear edge of a temporarily stationary sheet.

Accordingly the present invention provides for use in conjunction with the automatic registering or like devices of a printing machine or other machine operating on paper sheets the combination of endless tapes of the type hereinabove specified for the conveyance of the sheets to the registering or like devices and means to permit of the endwise assembly of the conveyor tapes on their driving shafts.

The term "driving shafts" is used herein to indicate the shafts, spindles, rollers or like members customarily employed in band-conveyors of the type with which this invention is concerned. Usually only one of said shafts or like members is driven and the other one which is freely mounted for rotation is a follower.

Any convenient means may be adopted to allow of the endwise insertion of the tapes. For example the shaft bearings at one side of the machine may be so constructed as to be easily removed when required. In one construction according to the invention one or each of the shafts or spindles upon which the tapes are mounted, is in two portions with a detachable coupling between them.

The accompanying drawings (largely diagrammatic) illustrate by way of example, two arrangements which may be employed for permitting the endwise insertion and removal of the conveyor tapes.

Figure 1 is a perspective view showing a portion of a sheet-feeding machine in which endless bands according to this invention are employed.

Figure 2 is a perspective view of one of

the tape rollers showing one method for the insertion of the conveyor tapes, and

Figure 3 is a sectional elevation of a tape roller showing an alternative arrangement 5 for the insertion of the tapes.

Like reference numerals indicate like parts in the various figures.

In the machine illustrated in Figure 1, the sheets are conveyed down a register board 10 by a series of endless tapes 11 extending between upper and lower tape rollers 12, 13. The roller 13 is set into the board 10 and the central portion of the latter is constructed by removable panels 14 located between the upper and lower laps of the conveyor tapes.

The sheets are carried forward one at a time on the upper laps of the tapes 11 to a position in which the leading edge of the sheet comes into contact with and is temporarily arrested by two or more registering stops 15. While the sheet is thus arrested a side lay 16 comes into operation after which the sheet is passed on say to a printing machine.

In this example the conveyor tapes are driven by the upper tape roller 12 (the driving mechanism being shown in Figure 1 by chain lines at 17) while the lower roller 13 round which the tapes pass is an idler or follower. Conveniently the construction shown in Figure 2 is adopted for the upper roller 12 and that shown in Figure 3 for the lower roller 13. In the Figure 2 construction the roller is in two portions 18, 19 the inner ends of which are carried in a central bearing block 20. The inner ends of the rollers meet in a half-lap joint and are maintained in driving engagement by a cap 21 (Figure 1) which is bolted on to the top of the bearing block.

The drive for the conveyor tapes is transmitted to the outer end of the section 18. Near the outer end of each section a flexible joint 27 is provided in order to permit of each section being swung upwards into a position clear of the bearing block 20. When the tapes are to be inserted on or removed from the section 18 the cap 21 is removed and the inner end of the section lifted clear of the block as indicated in Figure 2. Similarly for the insertion or removal of tapes on or from the roll section 19, the latter is swung clear of the block about the joint 27, and in this way the section presents a free end over which the tapes may be passed.

It is of course also necessary to present a free end for the passage of the tapes over the lower roller 13. In the construction shown in Figure 3 the roller is in one piece supported at its ends by bearings which are so constructed as to permit of one end of the roller being freed when required. The roller is tubular and at one end is mounted on a fixed pin 22 with a ball race 23 between the pin and the wall of the roller.

The pin 24 which supports the opposite end of the roller is screw-threaded in the supporting member 25 so that it may be moved in the direction of the axis of the roller. The outer end of the pin 24 is formed with a knurled head 26 by which the pin may readily be manipulated. When it is desired to free one end of the roller the pin 24 is unscrewed, which leaves the left-hand end of the roller free for the insertion of tapes. The arrangement may be such that when the pin 24 is withdrawn the roller may be slid to the left and then completely removed.

It will be understood that the construction shown in Figures 2 and 3 are given by way of example only and it is not necessary that the upper roller should be in two portions while the lower roller is in one piece. If desired both rollers may be provided with the same means for permitting the endwise insertion of the tapes. The upper or driving roller may be in a single length without a central bearing. In this case the end bearing would be split, so that on removal of one half of the bearing the roller could be lifted into a position in which it presented a free end for the passage of the conveyor tapes over the roller.

The invention is applicable in general to sheet-feeding devices in which the bands by which a sheet is conveyed continue to advance after that sheet has been brought to rest and while at least a portion of the sheet still overlies the bands. The endless bands may be used either alone or in conjunction with the usual feed board located between the upper and lower laps of the bands.

What I claim as my invention and desire to secure by Letters Patent is:

1. In sheet-feeding apparatus operating in conjunction with registering or like devices for the sheets, the combination with endless tapes for conveying the sheets to the registering devices, said tapes being of the type constituted "endless" during their manufacture, of driving shafts for the tapes aforesaid, and means associated with said driving shafts, to permit of the endwise insertion thereon and withdrawal therefrom of the tapes, the means aforesaid being constituted, as to one at least of the driving shafts, by a transverse division of said shaft into two sections coupled at their inner ends by a releasable driving connection arranged when released to free said inner ends for the passage thereover of the tapes.

2. In a sheet-feeding apparatus operating in conjunction with registering or like devices for the sheets, the combination with endless tapes for conveying the sheets to the registering devices, said tapes being of the type constituted "endless" during their manufacture, of driving shafts for the tapes

- aforesaid, and means associated with said driving shafts, to permit of the endwise insertion thereon and withdrawal therefrom of the tapes, said means being constituted as to one at least of the shafts by a joint in the length thereof and by means to allow of said joint being broken and of the portions of the shaft on opposite sides of the joint being moved out of alignment into positions in which the inner ends of said portions are "free" for the passage thereover of the tapes.
3. In sheet-feeding apparatus operating in conjunction with registering or like devices for the sheets, the combination with endless tapes for conveying the sheets to the registering devices, said tapes being of the type constituted "endless" during their manufacture, of driving shafts for the tapes aforesaid, and means associated with said driving shafts, to permit of the endwise insertion thereon and withdrawal therefrom of the tapes, said means being constituted as to one at least of the driving shafts by a transverse division of said shaft into two sections having their inner ends formed to engage one another in a driving connection, a split bearing, at least one half of which is readily removable, arranged to support the inner ends of the shaft sections and to maintain said ends in driving engagement, and flexible joints in the shaft sections near the outer ends thereof.
4. In sheet-feeding apparatus operating in conjunction with registering or like devices for the sheets, the combination with
- endless tapes for conveying the sheets to the registering devices, said tapes being of the type constituted "endless" during their manufacture, of driving shafts for the tapes aforesaid, and means associated with said driving shafts, to permit of the endwise insertion thereon and withdrawal therefrom of the tapes, said means being constituted as to one at least of the driving shafts by a transverse division of said shaft into two sections having their inner ends formed to engage one another in a driving connection, a split bearing, at least one half of which is readily removable, arranged to support the inner ends of the shaft sections and to maintain said ends in driving engagement, and flexible joints in the shaft sections near the outer ends thereof.
5. In sheet-feeding apparatus operating in conjunction with registering or like devices for the sheets, the combination with endless tapes for conveying the sheets to the registering devices, said tapes being of the type constituted "endless" during their manufacture, of driving shafts for the tapes aforesaid, one of said shafts being divided at a point between its ends into two sections having a detachable coupling between them, and the other shaft being supported as to one of its ends in a detachable bearing.

In testimony whereof I affix my signature,
HEADLEY TOWNSEND BACKHOUSE.
